[57] ABSTRACT

In a bag-making machine, a work unit such as a handle-applying station is independently displaceable in two directions perpendicular to one another and is driven by a drive shaft disposed at a fixed location, a propeller shaft having length compensating means connecting the drive shaft to a power input shaft for the work unit. Either the input shaft or the drive shaft is in the form of a cantilever-mounted hollow shaft connected to the propeller shaft by a joint which is pivoted to an annular flange attached to the hollow shaft and which is also pivoted to a sleeve, the propeller shaft passing through the centrally free joint and through the hollow shaft, said sleeve making a positive rotary drive connection to the propeller shaft but being longitudinally displaceable thereon.

BAG-MAKING MACHINE

The invention relates to a machine for making bags or sacks, particularly carrier bags, from heat-sealable material, comprising a work unit, for example a handle-applying station for the bags, which unit is independently displaceable in two directions perpendicular to one another and is driven by a drive shaft disposed at a fixed location, a power input shaft for the work unit, and a propeller shaft connecting said input and drive shafts by respective joints located adjacent the input and drive shafts, the propeller shaft being provided with length compensating means.

With such work units, and at least with handle-applying stations for welding injection-moulded handles to bag material, there is a requirement that the intervals between successive handles be very accurately set to a distance depending on the size of the bags being made. For example, it should be possible to set the centre line of the handle-applying station at a very accurate distance from the centre line of a welding bar which is located downstream thereof and serves to form the side seams of the bags after the handles have been welded on. More particularly, this spacing between the centre lines should be exactly $2\frac{1}{2}$ or $1\frac{1}{2}$ times the width of the bags being made ($2\frac{1}{2}$ times for narrow bags and $1\frac{1}{2}$ times for wider bags). In order to suit all the possible settings that might be encountered in practice, it should therefore be possible to adjust the work unit in the longitudinal direction of the machine by a distance equal to at least the width of the widest possible bag size, for example 700 mm. Similar considerations apply to setting the work unit in a direction transversely of the machine. In this case, a characteristic datum, for example the centre line of the welding jaw for the handle in the case of a handle-applying station, must be at a very special spacing from a fold line in the bag material, namely a distance equal to the desired depth of the bags being made. Although it is possible to set up the machine so that the fold line in the bag material is spaced from the handle welding jaw of the handle-applying station by a distance exactly equal to the bag depth, the units for folding the bag material are rigidly built into the machine whereas the dimensions of the bag material are likely to fluctuate. These fluctuations will result in fluctuations in the depths of the bags; they occur gradually rather than suddenly and can amount up to 2 cm. Although such a large variation in the depth of the bags is immaterial as far as the bags are concerned, they must be taken into account during bag manufacture by adjusting the spacing of the datum, i.e., the centre line of the handle welding jaw, from the fold line of the bag material. If no adjustment were to be made, the handles would be welded on either too far down the bag, in which case the upwardly projecting bag material would interfere with a good grip being obtained on the handles by the user, or too high up the bag, in which case there might be insufficient bag material to which to weld the handles, or the handles might miss the bag material altogether. Accordingly, the fluctuations in the dimensions of the bag material must be compensated by changing the transverse positions of the tools effecting the application of the handles. However, since the units for folding the bag material are rigidly built into the machine and not adjustable during operation, fluctuations in the depth of the bags are compensated by adjusting the position of the handle-

applying station in a direction transversely of the machine. To make this possible, the mounting and the drive means for the handle-applying station must be movable, in extreme cases up to about 50 to 60 mm.

- 5 It is known that a cardan shaft provided with length compensating means can be used to transmit mechanical power from a fixed point to one of which the position is variable in two directions. A prerequisite for this is that the extent of displacement of the movable point 10 relatively to the fixed point in a direction lengthwise of the cardan shaft be considerably smaller than the smallest possible distance between the two joints of the cardan shaft or, when the movable point is closest to the fixed point, the two points be spaced apart at a distance larger than the smallest retracted length of the cardan shaft.

The aim of the invention is to provide a drive arrangement for the aforementioned case in which the movable point that is to be supplied with mechanical power moves within considerably larger limits than those determined by the closest spacing of the movable point relatively to the fixed point, so that the bag-making machine need not be unnecessarily long, i.e., there can be a small spacing between the work unit and the drive shaft.

According to the invention, a machine for making sacks or bags for heat-sealable material comprises a work unit which is independently displaceable in two directions perpendicular to one another and is driven 20 by a drive shaft disposed at a fixed location, a power input shaft for the work unit, and a propeller shaft connecting said input and drive shafts by respective joints located adjacent the input and drive shafts, the propeller shaft being provided with length compensating means, wherein the input shaft or the drive shaft is in the form of a cantilever-mounted hollow shaft and the associated joint is a centrally free joint comprising a ring, particularly the pivot ring of a universal joint, which ring is pivoted to an annular flange attached to the hollow shaft and which is also pivoted to a sleeve, said propeller shaft passing through the centrally free joint and through the hollow shaft, said sleeve making a positive rotary drive connection to the propeller shaft but being longitudinally displaceable thereon.

45 In this way, the central portion of the propeller shaft, which may be splined, may be as long as required (within the limits set by any problems that may arise through oscillations) and its entire length may be utilized for displacing the movable point. More particularly, the movable point can be brought very close to the fixed point of the power supply. Although particular reference has been made to the use of a cardan shaft for the propeller shaft, the advantages of the invention can also be obtained with other types of propeller shafts, particularly those having homokinetic joints or joints using fixedly screwed rubber or resilient transmission elements.

An example of the invention will now be described with reference to the accompanying drawings, wherein:

60 FIG. 1 is a diagrammatic fragmentary plan view of a bag-making machine, and

FIG. 2 is an enlarged sectional view of the portion encircled at A in FIG. 1.

65 Referring to FIG. 1, a drive motor 1 operates through gearing 2 to turn a drive shaft 3 which is at a fixed location. The drive shaft 3 terminates at a power supply point 4 comprising a universal joint 5. The kinematic

point of the universal joint 5 is designated 6. At this kinematic point, the longitudinal centre line of the drive shaft 3 intersects that of a propeller shaft 7 of which substantially all the central portion is provided with a splined profile. A welding bar 9 having a longitudinal centre line 10 serves to apply transverse weld seams to bag material 19 which is fed in the direction of the arrow a and comprises a two-ply web containing fold lines adjacent the edge 18. A handle-applying station 11 having a longitudinal centre line 14 is operated in synchronism with the machine cycle to weld handles at predetermined intervals to the web 19. For this purpose, the handle-applying station comprises a welding jaw 12 which has a longitudinal centre line 13 and is reciprocatable in the direction of the arrow a and back again in synchronism with the machine cycle. The transverse centre line of the welding jaw 12 coincides with the longitudinal centre line 14 of the handle-applying station. The latter includes a hopper 34 for injection-moulded handles.

The handle-applying station 11 is displaceable, as shown in broken lines, in a direction parallel to the web movement a through a distance L and, independently thereof, in a transverse direction through the distance Q. Within the station 11 there is a universal joint having a kinematic point 15 and to be described more fully hereinafter. From a constructional point of view, the inclination of the central portion 7 of the propeller shaft relatively to the drive shaft 3 and a power input shaft 21 (FIG. 2) of the station 11 is limited between the positions shown at 16 and 17 in chain-dotted lines in FIG. 1. Accordingly, the station 11 is not freely displaceable within a rectangle having the dimensions Q and L but within a hexagon that is shown by the cross-hatching in FIG. 1. In the illustrated example, the transverse centre line 14 of the welding jaw 12 of the handle-applying station is set to a spacing D from the centre line 10 of the welding bar 9, this spacing being equal to 1½ times the width B of the carrier bags to be made. The longitudinal centre line 13 of the jaw 12 is set at a spacing T from the lower folded edge 18 of the web 19 equal to the desired depth of the bags to be made. Since the width of the web 19, and thus the depth of the bags made therefrom, can fluctuate within wide limits but the position of the base fold line 18 is fixed once the machine has been set up, any fluctuation can be compensated only by changing the transverse position of the station 11 with a view to keeping a constant spacing S between the top edges of the web 19 and a weld seam by which the handles are secured to the web 19.

The displaceability of the handle-applying station in two directions and independently of one another, and the close proximity of the station 11 to the stationary point 4 of power supply, are obtainable with the aid of the propeller shaft and universal joint as illustrated in FIG. 2. In FIG. 2, a wall 20 of the handle-applying station is cast in one piece with a bearing sleeve which permits cantilever mounting of the aforementioned input shaft 21, which is hollow. Although the shaft 21 is quite short, roller bearings are used to support only its right-hand end. On the left-hand side, the shaft 21 carries a pinion 23 which engages a drive gear 24 of the

handle-applying station. The input shaft 21 is connected to the central portion 7 of the propeller shaft by a universal joint 25 having the aforementioned kinematic point 15. By reason of the splines on the propeller shaft, the shaft 21 is in positive drive connection therewith but axially displaceable relatively thereto. The universal joint 25 is centrally free, i.e., a shaft may be pushed through the centre of the joint. This central freedom is obtained by means of a pivot ring 26 carrying four radially inwardly projecting pivots 27 which are equally spaced circumferentially of the ring. The upper half of the joint 25 shown in cross-section in FIG. 2 should be imagined as being turned through 90° relatively to the lower half. Each pair of opposed pivots 27 provides a pivotal connection to a respective bifurcated member 28 or 29 containing complementary bearing sleeves. One of the bifurcated members by a sleeve 30 which is axially displaceable on the central portion 7 of the propeller shaft and the other bifurcated member (29) is connected to the power input shaft 21 by means of an annular flange 31. The sleeve 30 is displaceable along the propeller shaft within very wide limits determined by the unsupported length of the propeller shaft portion 7 (which could give rise to oscillations at high speeds). To protect the interior from dirt and foreign matter, the bearing sleeve on the wall 20 is connected to a bellows-like cover 32 which carries a sealing ring 33 for engaging the splines of the propeller shaft but permitting rotation of the shaft relatively to the cover.

Apart from the aforementioned use of a centrally free universal joint, other basic constructions may be employed. It should also be mentioned that the power input is carried 21 and universal joint 25 need not just be provided on the wall of the handle-applying station facing the upstream direction but could also be provided on the downstream wall. Further, the bifurcated members free universal joint need not be disposed on the left-hand side of the input shaft 21 as illustrated but could be on the right-hand side. Still further, the universal joint 25 could, instead of being associated with the input shaft 21, be provided for the drive shaft 3.

I claim:

1. A machine for making sacks or bags from heat-sealable material, comprising a work unit which is independently displaceable in two directions perpendicular to one another and is driven by a drive shaft disposed at a fixed location, a power input shaft for the work unit, and a propeller shaft connecting said input and drive shafts by respective joints located adjacent the input and drive shafts, the propeller shaft being provided with length compensating means, wherein the input shaft or the drive shaft is in the form of a cantilever-mounted hollow shaft and the associated joint is a centrally free joint comprising a ring which is pivoted to an annular flange attached to the hollow shaft and which is also pivoted to a sleeve, said propeller shaft passing through the centrally free joint and through the hollow shaft, said sleeve making a positive rotary drive connection to the propeller shaft but being longitudinally displaceable thereon.
